(**) Term: **14 Years**

(57) **CLAIM**

(21) Appl. No.: **29/230,977**

I claim the ornamental design for a dome shaped viewing
portal, as shown and described.

(22) Filed: **May 27, 2005**

DESCRIPTION

(51) **LOC (8) Cl.** **25-02**

FIG. 1 is a perspective view of the dome shaped viewing
portal showing my new design.

(52) **U.S. Cl.** **D25/52**

FIG. 2 is a front view of the dome shaped viewing portal.

(58) **Field of Classification Search** D25/52;
D12/404; 52/405

FIG. 3 is a back view of the dome shaped viewing portal.

See application file for complete search history.

FIG. 4 is a top view of the dome shaped viewing portal; and,
FIG. 5 is a bottom view of dome shaped viewing portal.
